SMOKING PIPE

Robert J. Lemp, Woodhaven, N. Y.

Application November 5, 1949, Serial No. 125,700

1 Claim. (Cl. 131—222)

1

This invention relates to smoking pipes and relates more particularly to a novel pipe wherein the user may enjoy a free drawing condition at all times.

An important object of the invention is to provide an improved pipe wherein the bowl is formed in two sections which are completely detachable from each other to correct any situation tending to interfere with this free drawing action.

The smoking pipe of the present invention is to be distinguished from pipes wherein the bowl is supported in a socket and is removable therefrom for the purpose of cleaning. In such pipes the bowl section has one or a number of small openings in the lower wall, forming smoke passages. After a period of use, these openings become clogged and can only be cleaned with considerable difficulty. Moreover, if one starts to smoke and finds the openings clogged he can clean the pipe only by removing all the tobacco and starting fresh.

In accordance with the present invention the upper section of the bowl is formed with a continuous bore from top to bottom, the bore preferably being uniformly tapered and having its larger diameter at its upper end. This upper section is supported in interlocked relation on the lower bowl section which has a vertical opening leading to a bore through the stem section. When mounted as aforesaid, the bowl may be filled in the usual manner and the upper bowl section then detached from the lower section for the purpose of removing any tobacco particles in the vertical opening.

Alternatively, the pipe may be loaded while in detached relation, the user placing a finger over the lower end of the bore to prevent tobacco from falling through. He then mounts the upper filled section of the bowl on the lower section and proceeds to smoke while enjoying a free passage of the smoke through the lower end of this upper section. Should he experience a clogging action, the upper section is removed without disturbing the tobacco, the obstruction removed from the opening in the lower bowl section, and the parts replaced.

It will thus be apparent that a further object of the present invention is to provide a two-section bowl wherein the only place any obstruction can occur is in the lower bowl section which is readily accessible.

In the drawings:

Fig. 1 is a side elevation of a smoking pipe embodying the present invention.

Fig. 2 is an exploded view showing a central section taken through the two bowl sections.

2

Fig. 3 is similar to Fig. 2 but shows the parts in assembled relation.

Fig. 4 is a plan view of the lower surface of the upper bowl section.

Fig. 5 is a broken plan view of the lower bowl section and a portion of the stem.

Fig. 6 is a broken section showing a modified form of the invention.

Fig. 7 is a broken section showing another modified form of the invention.

The several forms of the invention differ mainly in the particular means for attachment of the upper bowl section to the lower. Inasmuch as a smoker who desires to enjoy a completely free draw might remove the upper section a number of times during his smoke, it is preferable to employ some quick-acting joining means such as a bayonet type of joint or an interrupted thread, although an ordinary screw thread may be used.

20 The first form of the invention shown in Figs. 1 to 5 effects locking action by about a quarter turn of one part relative to the other. The upper bowl section 10 is of the usual external contour and is formed with a vertical, tapered bore 11. 25 Some taper is preferable to a bore of uniform diameter since the taper helps to retain all the tobacco in the upper bowl section. The degree of taper is a matter of choice, the important consideration being that the bore be substantially uninterrupted, e. g., characterized by the absence of a perforated lower wall.

At its lower end the upper bowl section is formed with a seat 12 and extending below such seat there is formed an annular projection or

35 male portion 13 whose contour is generally oval or elliptically shaped and whose side walls are undercut. The lower bowl section 14 is formed with an annular seat 15 of the same external diameter and contour as seat 12 and which receives the latter face-to-face contact to prevent leakage.

40 The upper wall of the lower bowl section is provided with an elliptical opening or female portion 16 shaped and proportioned as to size as to receive the male portion 13, the walls of such portions being inclined as shown to secure the desired dove-tailed or interlocking relation. Thus when the male portion is inserted in the female portion and given a partial rotation the upper section is locked to the lower section. An internal annular seat 17 is provided at the lower

45 end of female portion 16 which receives the lower surface 18 of the upper projection 13.

50 A tapered opening 19 leads downwardly from seat 17, the upper end thereof being preferably of the same diameter as the diameter of the lower end of bore 11 with which it is aligned

when the parts are joined. The lower end of bore 19 communicates with a horizontal smoke passage 20 in stem section 21.

The removable mouthpiece 22 is carried by the stem section, the particular joining means forming no part of the present invention.

In use, it is preferred to first remove the upper bowl section from the lower, place one's finger over the lower end of tapered bore 11 and then fill the bore with tobacco, compressing the mass as much as desired, and leaving no part of the mass extending below the lower end of the bore. The upper bowl section is now mounted on the lower bowl section and the user lights the pipe and proceeds to smoke in the usual fashion.

If any obstruction is experienced in the smoke passage, the upper bowl section is removed, the obstruction cleared from the lower bowl section as by blowing out the offending particle, the tobacco in the lower end of bore 11 slightly compressed upwardly, and the parts re-assembled. Any tarry residues in the lower end of the bore or in openings 19-20 can be readily removed, and the pipe always retained in prime smoking condition.

In the modified form of the invention shown in Fig. 6 the construction is largely the same as in the first embodiment except that in order to secure a more positive seal between the bowl sections, each of meeting surfaces 12 and 15 of the upper and lower bowl sections, respectively, are formed with annular recesses 24 and 25 and a metal or plastic ring 26 is secured, as by means of cementing, in one of such recesses, preferably the lower one. Thus, when the bowl sections are assembled a more nearly air-tight seal is effected.

In the second modified form shown in Fig. 7 the upper section 27 has a bore 28 of substantially uniform diameter throughout its length and the lower section 29 has a tapered opening 30 whose upper end is of substantially the same diameter as the lower end of bore 28 and which leads to the smoke passage 31 in the stem section 32.

In this instance, the meeting surface 33 and 34 of the upper and lower bowl sections, respectively, are ground flat and are formed with annular recesses 35 and 36 which receive ring-shaped magnets 37 and 38 although only one of the rings may be magnetized. When assembling the bowl sections, the upper section may be moved across surface 34 with a wiping action to remove any particles on the meeting surfaces.

While three forms or embodiments of the in-

vention have been shown and described herein for illustrative purposes, and the construction and arrangement incidental to three specific applications thereof have been disclosed and discussed in detail, it is to be understood that the invention is limited neither to the mere details or relative arrangement of parts, nor to its specific embodiments shown herein, but that extensive deviations from the illustrated forms or embodiments of the invention may be made without departing from the principles thereof.

What I claim is:

A smoking pipe including a bowl formed in two superimposed sections provided with meeting surfaces and a stem portion leading generally horizontally from the lower section, such stem portion having a smoke passage therein, the upper section having a tapered bore extending from its upper to its lower end and being of smaller diameter at its lower end, the upper surface of the lower section having a tapered bore leading into the smoke passage, the upper end of said bore being of substantially the same size as, and being axially aligned with, the lower end of the upper section bore when the upper section is mounted on the lower section, and means for releasably securing the meeting surfaces of the bowl sections together, such means comprising a generally oval-shaped male portion of dovetailed cross-sectional contour extending outwardly from one of the surfaces, the other surface having a recess shaped complementary to and which receives the male portion in interlocked relation upon a partial rotation of the parts.
